US00D927506S

(12) **United States Design Patent** (10) **Patent No.:** **US D927,506 S**
Ford (45) **Date of Patent:** **** Aug. 10, 2021**

(54) **DISPLAY SCREEN OR PORTION THEREOF
WITH A GRAPHICAL USER INTERFACE
INPUT SELECTOR**

(71) Applicant: **AMAZON TECHNOLOGIES, INC.**,
Seattle, WA (US)

(72) Inventor: **Keith W. Ford**, Seattle, WA (US)

(73) Assignee: **AMAZON TECHNOLOGIES, INC.**,
Seattle, WA (US)

(**) Term: **15 Years**

(21) Appl. No.: **29/674,370**

(22) Filed: **Dec. 20, 2018**

Related U.S. Application Data

(62) Division of application No. 29/576,333, filed on Sep. 1, 2016, now Pat. No. Des. 842,310, which is a division of application No. 29/512,509, filed on Dec. 19, 2014, now Pat. No. Des. 768,702.

CLAIM

The ornamental design for a display screen or portion thereof with a graphical user interface input selector, as shown and described.

DESCRIPTION

FIG. 1 is a front view of a display screen or portion thereof with a graphical user interface input selector; and, FIG. 2 is a second embodiment thereof.

The broken lines showing a display screen or portion thereof and elements of the graphical user interface illustrate portions of the article and form no part of the claimed design.
